DESIGN FOR A DRESS

Leah Asteroff, New York, N. Y.

Application January 12, 1942, Serial No. 105,154

Term of patent 3½ years

To all whom it may concern:

Be it known that I, Leah Asteroff, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is a rear view of the dress shown in Fig. 1.

The characteristic feature of my design resides in the combination on the shirt waist dress disclosed of the specific rear blouse portion which is yoked and tucked as shown.

I claim:

The ornamental design for a dress, substantially as shown and described.

LEAH ASTEROFF.
